ANNEALING FURNACE

Filed Feb. 3, 1947

UNITED STATES PATENT OFFICE

2,476,204

ANNEALING FURNACE

Philip Mastercole, Steubenville, Ohio; Mary Mastercole, executrix of said Philip Mastercole, deceased, assignor to Mary Mastercole, Steubenville, Ohio

Application February 3, 1947, Serial No. 726,135

1 Claim. (Cl. 263—46)

1

My invention relates to annealing furnaces of the type described for example in the Clarence B. Hoak Patent No. 2,239,523, which involves the heating of annealing boxes or the like by both radiation and convection. In the present instance, the furnace may be of the portable hood type or not, as may be desired.

In the said patent, radiating walls composed of slabs are mounted interiorly of the furnace hood, the walls extending only partway to the furnace roof and the gas burners entering through the side walls of the furnace, the combustion spaces or chambers being located between the radiating walls and the adjacent side walls of the furnace. A substantial or major portion of the heat is transmitted through the radiating wall to the annealing box or other work pieces in the furnace, some of the heated gas, however, passing over the tops of the radiating walls into the annealing chamber, so that there is heating both by radiation and convection.

The present invention has for its object the provision of a furnace structure of the character referred to wherein the radiating walls or slabs are mounted in place and connected to the side walls, in an improved manner, without the necessity of using anchoring bolts.

As shown in the accompanying drawing, Figure 1 is a vertical sectional view through a portion of an annealing furnace equipped with my invention; Fig. 2 is a view taken on the line II—II of Fig. 1; Fig. 3 is a view taken on the line III—III of Fig. 1; Fig. 4 is a view showing a modification of the structure of Fig. 1, and Fig. 5 shows still another form of the invention.

The furnace is shown as provided with the usual hearth or foundation 5 and the usual metal shell comprising plates 6 and buck stays 7. Where the furnace is to be of a portable type, a metal bottom plate 8 will be employed as part of the metal structure.

The side walls of the furnace will be made of insulating bricks 9 which are of a porous nature, so that they can be sawed and cut to form notches as hereinafter explained.

Slabs or blocks 10 of highly refractory material such as silicon carbide serve as heat-radiating elements through which heat will be transmitted from the flames produced by the burner or in the spaces between the blocks 10 and the side wall bricks 9. Where the slabs 10 are tongued and grooved on their horizontal edges as shown at 11, mortar will not be required at these horizontal joints. The slabs have grooves in their vertical edges for interlocking engagement with

ribs 12 that are formed on tie blocks or plates 13 which will be of material sufficiently refractory to withstand the high temperatures in the combustion space behind the radiating wall. 5 These tie plates are of T-shape at their outer vertical edges, as shown at 14 and these heads will interlock with complementally-shaped notches in certain of the bricks 9, the said notches being formed therein by sawing or otherwise. 10 The radiating wall slabs 10 are thus held in position. The usual burners 15 will supply gas for combustion. There is, in effect, a combustion chamber or space for each burner, as shown more clearly in Fig. 2, and these will be individually controlled so that there can be an even heating of an annealing box or work piece at the various points throughout the length of the furnace. This avoids overheating certain portions of the annealing box such as frequently occurs— 20 particularly at a mid point in the furnace.

Furthermore, the vertical length of the burner flame in the combustion chambers can be controlled, so that there can be greater or less radiation of heat at desired levels. When the furnace is first put into operation, gas can be supplied at a high rate to produce flames that may extend to and above the upper edges of the radiating walls. However, after initial heating has been had, the supply of gas will be reduced, 25 and the major portion of the heat to the work will be supplied by radiation from the slabs 10.

At the vertical tongues and grooves 12, horizontal tongues and grooves 11 and the T connections 14, no mortar is required, and there can be shifting of the members 12 and 13 under temperature changes, without damage to the joints.

Another advantage of the interlocking arrangement as between the slabs 10 and the tie plates 13 is that the slabs 10 can readily be replaced in case of damage, simply by lifting off as many slabs as is required to reach a slab in a particular vertical row that requires replacement, and without disturbing the slabs in the other rows or the tie plates 13.

45 In Fig. 4, I show an arrangement wherein tie plates 17 of somewhat different form than the plates 13 are employed. In this case, portions of the plates 17 are cut away as at 18 to provide crosswise communication between the combustion spaces. While the major flow of heated gases will be in the vertical paths provided by the plates 17, there will be some horizontal flow through the passageways 18. In some cases for example, the mid portion of the annealing box 55 will be sufficiently heated at an early stage, and

therefore, gas to the adjacent burners can be shut off, adequate heat to maintain the temperature at such mid portion of the box being secured by the small crosswise flow through the passageways 18. In this structure, the radiating blocks 19 are smooth along their horizontal edges instead of tongued and grooved as at 11 in Fig. 1. When required, mortar will be used at these joints. The ends of the tie plates 17 will be ribbed and have connection with the radiating wall and the side walls of the furnace in the same manner as in Fig. 2.

As to the dimensions of the small combustion chambers in front of each burner, they may suitably be about 10 inches square internal dimensions, as indicated in Fig. 2. It will be understood, of course, that the notches in the bricks 9 for the heads 14 of the tie plates 13 may be set at various distances inwardly from the metal shell 6, which will change the width of the combustion chambers in that direction. This may be desired in some instances where combustion chambers of certain particular dimensions are desired. Also, there will be instances where limitations of space will require that the radiating slabs be set closer to the insulating wall bricks 8, as when this improved furnace hood is to be placed on an old foundation. In that case, the notches in the bricks 9 for the flanges 14 will be cut closer to the outer ends of these bricks, and the slabs 10 of the tie plates therefore will be located closer to the bricks 9.

As shown in Fig. 5, the positions of the tongues and grooves in the tie plates 13 and the radiating slabs 10 may be reversed, so that the tie plates 21 have the grooves, and the radiating plates 22 can be rounded at their vertical edges to fit into the grooves 23 of the tie plates.

I claim as my invention:

An annealing furnace comprising a side wall

and a roof, radiating wall slabs disposed in interiorly-spaced relation to the side wall and in a plane generally parallel to the side wall, and extending to a plane spaced a substantial distance below the roof, tie elements having their outer ends held by the side wall, and interlocking surfaces along the vertical sides of the tie elements, positioned between the ends of adjacent slabs, the slabs having complementally formed loose-fitting interlocking surfaces, along their vertical edges, whereby the slabs may be dropped into assembled position with respect to the tie elements, the interlocking elements being formed of plates arranged in laterally-spaced planes that are perpendicular to the planes of the side wall and the slabs and extending from the lower edges of the radiating wall to approximately the upper edges thereof, each slab being co-extensive in height with its associated plates, and means for supplying fuel into the lower ends of the passageways formed by the slabs and plates.

PHILIP MASTERCOLE.
